UNITED STATES PATENT OFFICE

168,018

DETACHABLE SLIDE DENTAL MIRROR

Leonard Roy Cohn, New York, N. Y.

Application October 9, 1950, Serial No. 12,492

Term of patent 14 years

(Cl. D9—2)

To all whom it may concern:

Be it known that I, Leonard Roy Cohn, a citizen of the United States, and a resident of the city, county, and State of New York, have invented a new, original, and ornamental Design for a Detachable Slide Dental Mirror, of which the following is a specification, reference being had to the accompanying drawing, forming part hereof and in which:

Fig. 1 is a top perspective view of a detachable slide dental mirror, showing my new design.

Fig. 2 is a top plan view thereof;

Fig. 3 is a side elevational view thereof; and
Fig. 4 is an end elevational view thereof.

The drawing figures are shaded to indicate transparency of the mirror surface.

The dotted line showing of the toothbrush in Fig. 1 is for illustrative purposes only.

I claim:

The ornamental design for a detachable slide dental mirror, as shown.

LEONARD ROY COHN.
